UNITED STATES PATENT OFFICE.

THOMAS J. YOUNGLOVE, OF RICHMOND, VIRGINIA, ASSIGNOR OF ONE-HALF
TO THOMAS B. HICKS, OF RICHMOND, VIRGINIA.

DOOR-CHECK.

No. 851,193.

Specification of Letters Patent.

Patented April 23, 1907.

Application filed May 23, 1906. Serial No. 318,333.

To all whom it may concern:

Be it known that I, THOMAS J. YOUNGLOVE, a citizen of the United States, residing at Richmond, in the county of Henrico and State of Virginia, have invented a certain new and useful Door-Check, of which the following is a specification, reference being had therein to the accompanying drawing.

This invention relates to door checks and particularly to checks used in connection with the doors of closed carriages such as hacks, coupés and landaus and the like, the present invention being in the nature of an improvement upon the construction set forth in a co-pending application filed by me March 29, 1906, Serial Number 308,802.

The primary object of the present invention is to provide means for preventing the door from swinging open in case of failure to securely latch the door in the act of closing the same.

It frequently happens that in closing the door of a vehicle, through carelessness or by reason of the latch failing to operate properly, the door is left unlatched and as the vehicle starts the door is often thrown open leaving the same liable to come in contact with any kind of an obstruction such as a post or tree box with a result that the door is torn from its hinges. By means of the construction hereinafter described, the door even when not properly latched, is prevented from swinging open, and furthermore, when the door is thrown open all the way by hand, said door is checked in time to prevent the same coming in injurious contact with the adjacent wheel of the vehicle.

With the above and other objects in view, the invention consists in the novel construction, combination, and arrangement of parts as hereinafter fully described, illustrated and claimed.

In the accompanying drawings: Figure 1 is an inside elevation of a carriage door and a portion of the body of the vehicle, showing the improved door check applied thereto. Fig. 2 is an enlarged horizontal section through the same, showing the door open in full lines and closed in dotted lines. Fig. 3 is a longitudinal section through the guide rail showing the detent or catch.

Referring to the drawings 1 designates the door of a carriage or like vehicle embodying the side uprights 2 and 3, while 4 designates

the hinge post or upright forming a portion of the vehicle body to which the door is hinged as shown at 5.

In carrying out the present invention, I employ a tie bar 6 which extends horizontally across the door 1 between the side uprights 2 and 3, the outer end of said tie bar being secured to the adjacent upright 3 by means of a suitable fastener 7 and the inner end of said tie bar being provided with a tee-shaped extension 8 secured to the upright 2 by means of the fasteners 9. The tie bar thus ties the side uprights of the door together and forms an efficient brace for the door as a whole.

Connected to the vehicle body is a hinge piece embodying a stationary member 10 secured permanently to the body by screws or other suitable fasteners as indicated in Fig. 2 and the detachable section 11, the members 10 and 11 being constructed to form an eye 12 which pivotally receives one end of an open center link 13, the opposite or outer end of which straddles a guide rail 14 secured to the door. The link 13 is further provided at its outer end with a runner 15 in the form of an eye which embraces the guide rail 14 and slides lengthwise thereof during the opening and closing movement of the door.

The guide rail 14 consists preferably of a stout rod round in cross section and having its opposite ends bent to the same side thereof and secured to the door by passing screws or other suitable fasteners therethrough and also through the tie bar 6 into the door. The guide rail 14 is provided in its inner side with a recess 16 extending lengthwise therein and forming a pocket in which operates a detent or catch 17 in the form of a spring secured at one end 18 within the recess and provided at a suitable point with a shoulder 19 which normally projects beyond the lateral plane of the inner surface of the guide rail as shown in Fig. 2 while the extremity of said catch is off set outwardly to form a projecting point 20. It will be seen that as the door is moved inward to its closed position, the eye or runner 15 rides over and passes the shoulder 19 and is engaged thereby so that even if the door be left unlatched, the said shoulder will prevent the runner 15 from moving backward along the guide rail and in this manner the door will be held from moving outward until sufficient force is brought

to bear against the door to overcome the spring tension of the catch or detent 17 whereupon the said catch will recede into the pocket 16 and allow the door to be opened.

5 The inwardly extending inner end 21 of the guide rail constitutes a stop shoulder against which the eye or runner 15 strikes when the door reaches the limit of its outward movement thus preventing the door from coming 10 in contact with the adjacent wheel which is shown at 22.

The guide rail 14 may be made of any suitable size and the catch or detent 17 may be made of any required stiffness so as to effectively engage the eye or runner 15 to prevent 15 the accidental opening of the door when left unlatched, and also to prevent the link from rattling when the door is closed.

I claim:

20 1. A check for preventing a vehicle door from striking against the adjacent wheel, the same being located adjacent to the hinged

edge of the door and embodying a hinge piece, a guide, a link pivotally connected to the hinge piece and having a sliding engagement 25 with the guide, and a spring which acts at a certain point in the movement of the door to resist and retard the movement of the link and also yields under excess pressure to allow further movement of the link.

2. A check for a vehicle door embodying a link connecting the vehicle door and body to limit the opening movement of the door, and means acting on the link at a certain point in the movement of the door to hold the door closed or approximately so with a frictional resistance which may be overcome by pressure against the door.

In testimony whereof I affix my signature in presence of two witnesses.

THOMAS J. YOUNGLOVE.
